UNITED STATES PATENT OFFICE.

WILLIAM J. GETSINGER, OF LOS ANGELES, CALIFORNIA.

TIE RETAINER.

1,423,208.

Specification of Letters Patent. Patented July 18, 1922.

Application filed April 11, 1921. Serial No. 460,349.

To all whom it may concern:

Be it known that I, WILLIAM J. GETSINGER, a citizen of the United States, residing at Los Angeles, in the county of Los Angeles and State of California, have invented new and useful Improvements in Tie Retainers, of which the following is a specification.

My invention relates to a new and useful necktie retaining device, the principal object 10 of my invention being to provide a relatively simple and efficient device that is adapted to be applied to the front portions of a soft or unstarched collar such as is now generally worn and which device, in addition to 15 engaging and retaining the necktie in proper position upon said collar, engages and retains the front or overfolded portions of said collar so as to prevent said folded portions from wrinkling and folding down- 20 wardly to the discomfort of the wearer.

With the foregoing and other objects in view, my invention consists in certain novel features of construction and arrangement of parts that will be hereinafter more fully 25 described and claimed, and illustrated in the accompanying drawings, in which:

Fig. 1 is a perspective view of a collar and a bow tie applied to said collar and retained in position by my improved device. 30 Fig. 2 is a rear elevational view of a bow tie and showing my improved retaining device applied thereto.

Fig. 3 is a horizontal section taken on the line 3—3 of Fig. 2.

Fig. 4 is a perspective view of the retaining device.

Referring by numerals to the accompanying drawings, which illustrate a practical embodiment of my invention, 10 designates 40 a strip or elongated rectangular section of thin flexible material such as celluloid, fiber board, resilient metal or the like, and which forms the body of my improved retaining device.

45 Formed through said body, preferably at a point near its center, is an aperture 11 through which pass hooks 12 that are formed on the inner ends of short sections 13 of wire or analogous material, the same extending in opposite directions away from the centrally arranged aperture and the outer ends of said sections of wire are rebent so as to form hook members 14 that pass through apertures 15 in the body 10 and 50 said apertures being located at short distances away from the centrally arranged

aperture 11. The terminal portions of the hook members 14 are pointed in order that said hook members may be readily engaged in the fabric of which collars are formed. 60

A device thus constructed, when applied to a bow tie of the form shown in Figs. 1, 2 and 3, is positioned between the rear portion of the loop L that passes around the center of the body B of the tie with the 65 pointed ends of hooks 14 disposed directly against the rear face of said body B, and, when the tie with my improved retaining device is positioned thereupon is applied to a soft or unstarched collar, the end portions of the body 10 are inserted beneath the front wings or folds of the collar and the hook portions 14 are engaged through the edges of the fabric forming the body of the collar, immediately to the sides of the 70 tabs that are provided with the front buttonholes; (see Figs. 1 and 3.)

When so positioned, the tie is firmly and conveniently held at the proper point on the collar, and as the front folded portions 80 of the collar are engaged by the hooks 14 and the end portions of the body 10 overlie the front folded portions of the collar, the latter will be held in position so as to present a neat appearance, and likewise it will 85 be retained in an uncrushed condition and consequently preventing discomfort to the wearer.

While I have shown and described my improved retaining device as being applied 90 to a bow tie, it will be readily understood that practically the same device may be utilized for retaining other forms of ties in position upon collars.

A necktie retaining device of my im- 95 proved construction is comparatively simple, may be easily and cheaply produced, and is very effective in performing its intended functions.

It will be readily understood that minor 100 changes in the size, form and construction of the various parts of my improved necktie retaining device may be made and substituted for those herein shown and described without departing from the spirit of my 105 invention, the scope of which is set forth in the appended claims.

I claim as my invention:

1. A necktie retaining device comprising 110 a strip of thin flexible material, a pair of short sections of wire having their inner ends secured to the central portion of said

flexible strip of material, the outer end portions of said sections of wire being rebent to form hooks which extend through the said strip of flexible material and project inwardly toward each other.

2. A necktie retaining device comprising a strip of thin flexible material in which is formed a pair of apertures, a pair of short sections of wire secured to said strip of material between said apertures and the outer end portions of said sections of wire being re-bent to form hooks that extend

through said apertures and project inwardly toward each other.

3. A necktie retaining device comprising 15 a strip of thin flexible material in which is formed a pair of apertures, and hooks secured to the central portion of said strip of thin flexible material, which hooks extend through said apertures and project inwardly toward each other.

In testimony whereof I have signed my name to this specification.

WM. J. GETSINGER.
